DESIGN FOR A BOTTLE

Glenn A. Mengle, Brockway, Pa., assignor to Wizard, Inc., Chicago, Ill., a corporation of Delaware

Application July 18, 1934, Serial No. 52,623

Term of patent 14 years

To all whom it may concern:

Be it known that I, Glenn A. Mengle, a citizen of the United States, residing at Brockway, in the county of Jefferson and State of Pennsylvania, have invented a new, original, and ornamental Design for a Bottle, of which the following is a specification, reference being had to the accompanying drawing, forming part thereof.

Fig. 1 is a top view, Fig. 2 is a front view, and Fig. 3 is a side view, of a bottle, showing my new design.

I claim:

The ornamental design for a bottle, substantially as shown.

GLENN A. MENGLE.
